METHOD OF MANUFACTURING LONG-DISTANCE TELEGRAPH AND TELEPHONE CABLES

Application filed January 5, 1927, Serial No. 159,204, and in Germany January 5, 1926.

My invention relates to a method of manufacturing long-distance telegraph and telephone cables in which added inductance is uniformly distributed along the conductors.

5 The conductors of such cables are, for the purpose of obtaining a uniformly distributed inductance or continuous loading, surrounded with a layer of magnetic material of high permeability. After the application of 10 the magnetic material to the conductor, the conductor together with the magnetic material is annealed, because the permeability of the magnetic material is considerably increased by heating it to a high temperature. 15 The annealing should preferably be carried out at a temperature of more than 1000° C. This involves, however, certain difficulties, because the copper conductor, which is simultaneously subjected to the annealing process 20 becomes brittle already at about 800° C.

According to my invention the annealing of the magnetic material applied to the conductor may be effected at any necessary temperature, by surrounding the conductor prior 25 to the application of the magnetic material with a layer of a bad conductor of heat. By this layer the conductor is sufficiently protected against the heat acting upon the magnetic material even at very high temperatures.

30 Particularly suitable for the heat insulating layer is a material which consists mainly of asbestos, such as for example a fabric of cotton and asbestos. The cotton is burned during the annealing process so that the layer 35 of asbestos remaining after the annealing can easily be removed due to loosening of the structure of fabric in consequence of the burning of the cotton. It may be advantageous to remove the heat insulating layer after the 40 annealing completely or partly in order to eliminate the danger of stretching the magnetic material when laying the cable. This removal is considerably facilitated due to the above mentioned destruction of the cotton by 45 burning. The air space remaining between conductor and the magnetic material after the removal of the asbestos and the cotton ashes may completely or partly be filled up with an insulating material, in well known man- 50 ner.

In order that the copper conductor remain as short a time as possible within the reach of the high temperatures, it is advisable to shorten the annealing process by blackening the magnetic material before applying it to the 55 fabric. As is well known, a material having a dull or blackened surface, absorbs heat quicker than a material with a bright, reflecting surface. By the aforementioned blackening of the magnetic material, for which any 60 suitable substance may be used, the heat absorption property of the material is increased and thus it is heated to the desired temperature within a shorter time than it takes to heat a bright surface material. A further advantage of the heat insulating intermediate layer 65 between conductor and coating is that the magnetic material is also electrically insulated from the conductor, so that the magnetic material may be heated and annealed 70 in a simple and convenient manner by an electric current passed through the magnetic material instead of carrying out the annealing process in a furnace.

In the accompanying drawing, 1 is a copper 75 conductor, which according to my invention is surrounded by a fabric 2 consisting of cotton and asbestos. Upon this fabric is wound a tape 3 of magnetic material.

Various modifications and changes may be 80 made without departing from the spirit and the scope of the invention, and I desire, therefore, that only such limitations shall be placed thereon as are imposed by the prior art.

I claim as my invention:

1. Method of manufacturing long distance telegraph and telephone cables loaded over the entire length with heat treated magnetic material, consisting in providing the cable with a heat insulating layer comprising a 90 mixture of an essential portion of non-combustible with combustible material before the magnetic material is applied and in then annealing the applied magnetic material, whereby the combustible material of said layer is 95 consumed and the remainder of the layer is left in a porous condition.

2. Method of manufacturing long distance telegraph and telephone cables loaded over the entire length with heat treated magnetic 100

material, consisting in providing the cable with a heat insulating layer comprising a mixture of asbestos and a combustible fabric filler before the magnetic material is applied and in then annealing the applied magnetic material, whereby the combustible filler of said layer is consumed and the remaining asbestos layer is left in a porous condition.

5 In testimony whereof I affix my signature.

ERNST FISCHER.
